[57] CLAIM

The ornamental design for a rear carrier for an off-road vehicle, as shown and described.

DESCRIPTION

FIG. 1 is a perspective view of a rear carrier for an off-road vehicle showing our new design, the vehicle shown in broken lines is for illustrative purposes only and forms no part of the claimed design;

FIG. 2 is a perspective view thereof;

FIG. 3 is a front elevational view thereof;

FIG. 4 is a rear elevational view thereof;

FIG. 5 is a top plan view thereof;

FIG. 7 is a side elevational view thereof, the opposite side elevational view being a mirror image;

FIG. 8 is a cross sectional view taken along section line 8—8 of FIG. 5; and,

FIG. 9 is a cross sectional view taken along section line 9—9 of FIG. 5.
